T. J. MCINTOSH,
REVERSIBLE FORK AND RAKE,
APPLICATION FILED FEB. 9, 1921.

Patented Oct. 11, 1921.

UNITED STATES PATENT OFFICE.

THOMAS JAMES MCINTOSH, OF DALZELL, SOUTH CAROLINA.

REVERSIBLE FORK AND RAKE.

1,393,299.

Specification of Letters Patent.

Patented Oct. 11, 1921.

Application filed February 9, 1921. Serial No. 443,576.

To all whom it may concern:

Be it known that I, THOMAS J. MCINTOSH, a citizen of the United States, residing at Dalzell, in the county of Sumter and State 5 of South Carolina, have invented certain new and useful Improvements in Reversible Forks and Rakes, of which the following is a specification, reference being had therein to the accompanying drawings.

10 This invention relates to a reversible fork and rake, and the object is to provide a simple and efficient device that is adapted to be employed for using different kinds of tools, in different positions, or "attachments", 15 upon a handle.

Another object of the invention is the construction of a simple and efficient ratchet device carried by a handle for holding the tool upon the handle at different angles, 20 with respect to the handle.

With these and other objects in view, my invention comprises certain novel combinations, constructions and arrangements of parts as will be hereinafter described, illustrated in the accompanying drawings, and more particularly pointed out in the appended claims.

In the drawings:

Figure 1 is a view in side elevation of a 30 device constructed in accordance with the present invention.

Fig. 2 is an enlarged, fragmentary, central, sectional view of the device.

Fig. 3 is a front view, in elevation, of one 35 of the ratchet plates, while

Fig. 4 is a sectional view, taken on line 4-4, Fig. 3, and looking in the direction of the arrows.

Fig. 5 is a fragmentary, perspective view 40 of the device, showing particularly the cap and the two ratchet plates therein.

Fig. 6 is a perspective view of the cap.

Referring to the drawings by numerals, 1 45 designates the handle, upon the inner end of which is ferrule 2, and on the outer end of the ferrule 2 is a cap 3. The cap 3 is provided with an elongated slot 4 which has at its opposite sides inwardly-extending extensions 5 which press tightly against the 50 longitudinal axis of the two ratchet plates 6.

The ratchet plates are similarly constructed; each ratchet plate comprises a straight body 7 having an inner aperture 8 and an outer aperture 9. The ratchet plate 55 is bent outwardly, at 10, and terminates in

a head 11. On the inner face of the head 11 are ratchet teeth 12 and in the center is a square aperture 13. In fastening the ratchet plates 6 in the handle, a suitable socket 14, Fig. 2, is formed and the ratchet plates are forced into the socket through the elongated slot 4 of cap 3 but before being forced into the socket 14, a short rivet or pin 15 is placed in the registering apertures 8, then after the plates are in the socket 14 a long rivet 65 or pin 16 is forced through the ferrule 2, handle 1 and through the registering apertures 9, securely fastening the ratchet device upon the handle.

A tool, such as blade 17, Fig. 1, or rake 18, Fig. 2, is provided with a head 19, which has ratchet teeth 20 on its sides, and these ratchet teeth 20 are engaged by the ratchet teeth 12 on the heads 11 of the ratchet plates 6, and bolt 21 and butterfly nut 22 fasten 75 the head 19 between the ratchet plates, after the tool has been adjusted to its desired position; for instance, in Fig. 1, the tool is shown as when the device is being used as a fork, or the tool can be moved to the dotted 80 position by loosening nut 22, then the tool can be used as a rake, or as a hoe, or the like.

The pair of inwardly-extending extensions 5, on cap 3, have a very slight resiliency, but grip the sides of the plates 6 sufficiently to cause the same to press relatively tightly against the head of the tool mounted between the plates but not sufficiently to hold the tool in the working condition upon the handle until the bolt and nut have been 90 applied.

A split or locking washer 23 is on bolt 21.

While I have described the preferred embodiment of my invention, and have illustrated the same in the accompanying drawings, certain minor changes or alterations 95 may appear to one skilled in the art to which this invention relates, during the extensive manufacture of the same and I, therefore, reserve the right to make such alterations or 100 changes as shall fairly fall within the scope of the appended claims.

What I claim is:

1. In a device of the class described, the combination with a handle, of a cap carried 105 by said handle and provided with an elongated slot having inwardly-extending extensions at opposite sides, a pair of ratchet plates extending through said slot and into said handle and engaged by said inwardly- 110

extending extensions of the cap, and a tool adjustably supported between the ratchet plates.

2. In a device of the class described, the combination with a handle provided with a socket at its inner end, of a ferrule on said socketed end, a cap provided with an elongated slot on the outer end of the ferrule, the slot of the cap registering with the socket in the handle, a pair of inwardly-extending extensions on the cap at opposite sides of the elongated slot, a pair of ratchet plates provided with a plurality of sets of registering apertures, said ratchet plates extending through the elongated slot of the cap and into the socket, said inwardly-extending extensions of the cap engaging the ratchet plates, a short pin in one set of said

apertures, a long pin extending through the ferrule and handle and extending through another set of the apertures of the ratchet plates, said ratchet plates extending outwardly intermediate their ends and terminating in heads, each head provided on its inner face with ratchet teeth and with an aperture, a tool having a head, ratchet teeth formed on the head of the tool and engaging the ratchet teeth of the ratchet plates, and fastening means extending through the apertures of the heads of the plates and the head of the tool and fastening the tool in an adjusted position between the ratchet plates, substantially as shown and described.

In testimony whereof I hereunto affix my signature.

THOMAS JAMES McINTOSH.
